FLEXIBLE INTERLOCKING SHINGLE

Stuart P. Miller, Scarsdale, N. Y., assignor to The Barrett Company, New York, N. Y., a corporation of New Jersey

Application July 21, 1936, Serial No. 91,717

10 Claims.

(Cl. 108—8)

This invention relates to shingles and more particularly to flexible composition shingles of the interlocking type.

One object of this invention is to provide a shingle which may be laid in interlocking relation with other similar shingles to prevent relative linear movement of the shingles in all directions.

Another object of this invention is to provide a shingle having a locking projection in one corner which may be interlocked with a slot in the opposite corner of another like shingle by inserting the projection in the slot and then rotating the shingles relative to each other to position them in desired aligned relationship.

Another object of my invention is to provide a durable roof construction of pleasing ornamental appearance constituted of overlapping courses of shingles having their exposed portions locked together to resist being blown up by the wind.

The shingle of my invention comprises a body portion provided with a locking member lying within the outline of the body portion and with a locking opening adapted to be entered by the locking member of a similar adjacent shingle. The locking member is preferably located adjacent a corner formed by the intersection of the forward or exposed edge of the shingle and a transverse edge of the shingle. This locking member may be defined by an opening, e. g. a notch, extending inwardly from the forward edge of the shingle and another opening extending inwardly from said transverse edge. The locking opening may be in the form of a slot located adjacent another corner of the shingle and constituted of a relatively narrow portion and a wider portion. The dimensions of the locking member and slot are preferably such that when the locking member is inserted into the opening and the shingles rotated relatively to each other the shingles are locked together to prevent relative linear movement in any direction.

For a more complete understanding of the invention reference may be had to the accompanying drawings which are illustrative of preferred embodiments of this invention and in which,

Fig. 1 is a plan view of a cutting layout illustrating a method of cutting one form of shingle of this invention from a sheet of roofing material;

Fig. 2 is an enlarged plan view of a shingle produced by cutting a roofing sheet in the manner shown in Fig. 1,

Fig. 3 is an enlarged fragmentary view showing two shingles of the type illustrated in Fig. 2 locked together,

Fig. 4 is a fragmentary plan view of a portion of a roof formed by laying the shingles of Figs. 1 to 3,

Fig. 5 is an enlarged detail view illustrating a method of locking the shingles of Figs. 1 to 3,

Fig. 6 is a plan view of a modified form of shingle in accordance with this invention,

Fig. 7 is an enlarged fragmentary plan view showing two shingles such as illustrated in Fig. 6 in interlocked relation,

Figs. 8, 10 and 12 illustrate other modified shingles in accordance with this invention, and

Figs. 9, 11 and 13 are fragmentary enlarged plan views showing two shingles of the type disclosed in Figs. 8, 10 and 12, respectively, in interlocked relation.

Referring more particularly to the drawings, Fig. 2 illustrates a shingle of general rectangular form constituted of a body portion 1 bounded by edges 2, 3, 4 and 5. Edge 2 may be considered, for purposes of description, the forward edge of the shingle, edge 4 the rear edge, and edges 3 and 5 the transverse edges. Forward edge 2 of the shingle is provided with a notch 6 extending inwardly therefrom adjacent transverse edge 3 and the latter edge is provided with a notch 8. The lower edge 9 of notch 8 is positioned above the closed-end notch 6 for a purpose hereinafter to be described.

Notches 6 and 8 define a locking member 10, bounded by edges 2 and 3 of the shingle and edges 9 and 11 of notches 8 and 6, and connected to the body of the shingle by neck portion 12. It will be observed that the locking member 10 is located within the rectangular outline of the body portion of the shingle defined by edges 2, 3, 4, 5.

The opposite transverse edge 5 of the shingle is provided with a locking opening 13, extending inwardly therefrom and constituted of a relatively narrow outer portion 14 and a wider inner portion 15. The narrow outer portion 14 of the locking opening is bounded by parallel upper and lower edges and the wider portion 15 is bounded by a continuation of the upper edge of the narrow portion, downwardly inclined edge 16, edges 17 and 20 perpendicular to forward edge 2 of the shingle, edge 18 parallel to forward edge 2, and upwardly inclined edge 19. Edge 17, it will be

noted, forms a locking shoulder separating the wide and narrow portions of the locking opening. The length of the wider portion 15 of the locking opening is substantially equal to the horizontal distance between the edge 11 of locking member 10 and the inner closed end of notch 8.

In order to provide a reversible shingle the locking construction adjacent forward edge 2 hereinabove described may be duplicated adjacent rear edge 4 of the shingle. Thus locking member 22 and locking opening 24 are similar in shape to locking member 11 and the locking opening 13 respectively.

Cutouts 25, 26 may be provided in transverse edge 5 of the shingle to provide notches for indicating the desired amount of overlap between successive courses of shingles.

The shingles may be cut from a roofing sheet in a manner which will be apparent from an inspection of Fig. 1 of the drawings. Locking openings 13, 24 and aligning notches 25, 26 may be formed by appropriately shaped cutouts along the longitudinal edges of the sheet. Notches 6 and 8 may be formed by cutouts formed within the body of the sheet. The sheet is severed into strips by longitudinal cut 27 and the strips are separated into individual shingle elements by transverse cuts 28. All of the cutting operations may advantageously be accomplished simultaneously by suitably disposed cutting members on the cutting cylinder or other cutting mechanism employed. The roofing sheet from which the shingles are cut may be constituted of a felt base impregnated and coated with bituminous waterproofing material, for example asphalt, and may have a layer of granular surfacing material partially embedded in the coating material.

The shingle may be assembled in interlocked relation in the manner shown in Figs. 3 and 5 to form a roof as illustrated in Fig. 4. In assembling the shingles the locking member 10 of shingle B is inserted through the locking opening 13 of shingle A and is moved to the position illustrated in Fig. 5, in which the closed end of notch 8 of shingle B is in engagement with the innermost edge 20 of locking opening 13 of shingle A. Shingle B is then rotated in counterclockwise direction until the lower edges of the shingles are in alignment. In this position the edge 9 of the notch 8 of shingle B is in locking engagement with the upper edge of the locking opening 13 of shingle A and the closed inner end of notch 6 engages the lower edge 18 of the locking opening. The side 11 of the locking member 10 of shingle B engages edge 17 of the locking opening 13 of shingle A. When the locking elements are thus positioned they provide an effective interlock between the shingles which resists relative linear movement of the shingles in all directions.

The modified form of shingle disclosed in Figs. 5, 6 and 7 differs from that of Fig. 2 chiefly in that the edges 31 of locking openings 30 are inclined with respect to transverse edge 5 instead of being perpendicular thereto. This construction provides projections 32 extending from locking members 33. The locking openings 35 differ from the locking openings of the shingle of Fig. 2 in that the edges 36 of locking openings 35 are parallel throughout their length to the edges 37 instead of being constituted of a parallel portion 65 and an inclined portion as in Fig. 2.

The shingle of Fig. 6 may be interlocked with another similar shingle as illustrated in Fig. 7. When thus assembled the projection 32 on locking member 33 of shingle D extends upwardly beyond edge 37 of the locking opening 35 of shingle C and adds to the strength of the interlock between the shingles. The exposed straight edge 36 of shingle C provides a pleasing roof design which differs from the design shown in Figs. 3 and 4.

The shingle illustrated in Figs. 8 and 9 is generally similar to that of Fig. 2 and differs from the latter shingle chiefly in that the horizontal edge 42 of locking opening 40 intersects the vertical edge 44 of the relatively wide portion of the locking opening instead of being connected thereto by an inclined connecting edge. This shingle may be laid in interlocking relation with another similar shingle as illustrated in Fig. 9. It will be observed that the right angled corner formed by the intersection of edges 42 and 44 of shingle E cooperates with the edge 11 of locking member 10 of shingle F in such manner that the shingles must be rotated relatively to each other through a relatively large angle in order to unlock them. Hence, the shingles are not likely to become unlocked under conditions of use.

The shingle shown in Fig. 10 is provided with the locking openings 46 constituted of slots 48 extending perpendicularly from transverse edge 5 and slots 52 leading into and extending at an angle from slots 48 between the ends of the latter. The shingle is provided with locking slots 54 extending inwardly from transverse edge 3 in alignment with the slots 48. Locking openings 25 constituted of notches 56 terminating in short slots 58 extend from edges 2 and 4 of the shingle. The closed inner ends of slots 58 are in alignment with the closed inner ends of slots 52. The slots 54, notches 56 and slots 58 define locking members 30, 60 adjacent each of the corners formed by the intersection of transverse edge 3 with edges 2 and 4 of the shingle.

The shingle of Fig. 10 may be interlocked with another similar shingle as illustrated in Fig. 11. When in interlocked relation, the closed end of slots 54 and 58 of overlying shingle G engage the closed ends of slots 48 and 52 respectively of shingle H. Relative horizontal movement of the shingles is prevented by interengagement of the slots 40, 52 and 58 and relative vertical movement is prevented by interengagement of slots 48 and 54. Thus it will be seen that the shingles when in interlocked relation resist relative linear movement in all directions.

The shingle of Fig. 12 differs from that of Fig. 10 chiefly in that the locking slots 62 are inclined instead of perpendicular with respect to transverse edge 5 of the shingle. Locking slots 64 extend perpendicularly from slots 62 and are 50 of such length that their closed ends are in horizontal alignment with the closed inner ends of slots 58. As will be seen by reference to Fig. 13, this shingle may be laid similarly to the shingles of Fig. 10, with the closed end of locking slot 62 55 in engagement with the closed end of slot 54 of an adjacent shingle and with the closed end of slot 64 engaging the closed end of slot 58 of the adjacent shingle.

It will be noted that the shingles of this invention are provided with interlocking means which enable the shingles to be locked together in such manner that they resist relative linear movement in all directions and may be separated only by relative rotation of the shingles with respect to each other. The shingles when laid form a roof of pleasing ornamental appearance constituted of courses of shingles having their exposed portions secured together so that they resist blowing up by the wind.

I claim:

1. An interlocking shingle comprising a body portion having a locking tongue defined by openings extending inwardly from two adjacent edges of the shingle intermediate the ends thereof, and

- said body portion being provided with a locking opening having a shoulder and adapted to receive the locking tongue of a similar shingle with the shoulder engaging portions of the tongue to prevent relative linear movement of said shingles in all directions.
2. An interlocking shingle comprising a body portion of general rectangular form, said body portion being provided with openings extending inwardly near one corner thereof and defining a locking member near said corner, said shingle being provided with a locking opening near the opposite corner provided with a shoulder intermediate the ends thereof, said last mentioned locking opening being adapted to receive the locking member of a similar shingle and to interlock therewith so that the shoulder engages the locking member.
3. An interlocking shingle of general rectangular form comprising a body portion having a forward edge and transverse edges, said shingle being provided in the neighborhood of one of said transverse edges with a locking member connected to said body portion by a neck of less width than the width of said locking member, said locking member lying substantially within the rectangular outline of said shingle, said body portion being provided adjacent the opposite transverse edge with a locking opening extending inwardly from said transverse edge, said locking opening being constituted of a relatively narrow portion and a wider portion.
4. An interlocking shingle comprising a body portion, a locking member constituted of a relatively wide portion and a relatively narrow portion, said relatively narrow portion connecting said relatively wide portion to the body portion of said shingle, said shingle being provided with a locking opening constituted of a relatively narrow portion and a relatively wide portion, the length of the relatively wide portion of said locking opening being approximately equal to the width of the relatively narrow portion of said locking member.
5. An interlocking shingle comprising a body portion of general rectangular form having a forward edge, a rear edge and transverse edges connecting said forward and rear edges, said shingle being provided with a locking opening extending inwardly from one of said transverse edges and with another locking opening extending inwardly from said forward edge in the neighborhood of said last named transverse edge, said locking openings forming a locking member connected to the body portion of said shingle by a neck portion, said shingle being provided with a third locking opening extending inwardly from the opposite transverse edge, said last named locking opening comprising a relatively narrow outer portion and a relatively wide inner portion, the length of said inner portion being equal approximately to the width of said neck.
6. An interlocking shingle comprising a body portion having a forward edge and transverse edges extending at an angle thereto, said shingle being provided with a locking opening extending inwardly from said forward edge, a locking opening extending inwardly from one of said transverse edges and a third locking opening extending inwardly from the opposite transverse edge and constituted of a relatively narrow portion and a relatively wide portion, the inner ends of said locking openings extending inwardly from said transverse edges being in substantially horizontal alignment and the inner end of said locking opening extending from the forward edge of said shingle being in substantial horizontal alignment with the lower edge of the wide portion of said locking opening extending from said opposite transverse edge.
7. A flexible interlocking shingle of general rectangular shape having in one lower corner a locking tongue defined by notches extending into the forward and side edges respectively of the element and having in the opposite corner an opening extending into the side edge, said opening being constituted of a relatively narrow portion and a wide portion the narrow and wide portions being connected by a shoulder extending at right angles to the longitudinal direction of the said opening and said opening being substantially parallel to the forward edge of the element.
8. A flexible interlocking shingle of general rectangular shape having in one lower corner a locking tongue defined by notches extending into the forward and side edges respectively of the element and having in the opposite lower corner an opening extending into the side edge, said opening being constituted of a relatively narrow portion and a wide portion the narrow and wide portions being connected by a shoulder extending at right angles to the longitudinal direction of the said opening and said opening extending at an angle other than a right angle to the side of the element.
9. A flexible interlocking shingle comprising a body portion of general rectangular shape having longitudinal edges and side edges, a locking member defined by a notch extending inwardly from one of said longitudinal edges and a notch extending inwardly from one of said side edges, said notches being spaced from one corner of the portion intended to be exposed to the weather and a locking slot extending into the side edge opposite the said corner, said locking slot forming a shoulder intermediate the ends thereof, said slot being adapted to receive a locking member of a similar shingle so that the said shoulder locks with one of the notches defining said locking member.
10. An interlocking shingle having upper and lower edges and non-complementary, non-homologous opposite side edges, a locking projection and a locking recess formed in the opposite side edges respectively, said locking projection being defined by openings extending inwardly from said lower edge and one of said side edges at locations spaced from a corner of said shingle, said locking recess being provided with a shoulder, the projection of said shingle being adapted to enter the recess of a like shingle when the vertical median lines of the shingles are at an angle to each other, and, after such engagement, to be locked with said recess of said like shingle when the said median lines are brought parallel to each other, said projection and recess being constructed and arranged so that when locked linear motion of the shingle with respect to the like shingle is prevented in all directions.

STUART P. MILLER.
